UNITED STATES PATENT OFFICE

2,679,087

SLUB CATCHER

Mansueto Asti and Louis Anterni, Woonsocket,
R. I., assignors to Falls Yarn Mills, a corpora-
tion of Rhode Island

Application August 7, 1952, Serial No. 303,126

9 Claims. (Cl. 28—70)

1

The invention relates to slub catcher and yarn guide.

One of the objects of the invention is to provide a slub catcher particularly adapted for detecting slubs and other imperfections in roving coming from a card tape condenser or other similar textile machine.

Another object of the invention is to provide a slub catcher of the above character so constructed as to permit the easy threading of roving therethrough.

Another object of the invention is to provide a slub catcher which may be adjustable for different diameters of roving.

Another object of the invention is to provide a slub catcher of the above character so constructed as to provide for detecting over-size roving to cause the same to be broken.

A more specific object of the invention is to provide a slub catcher adapted to be used in place of the heretofore standard traverse wire guide rod on card tape condenser machines.

With these and other objects in view, the invention consists of certain novel features of construction as will be more fully described and particularly pointed out in the appended claims.

In the accompanying drawings:

Figure 1 is a front elevational view of a slub catcher embodying our invention and attached to the traverse bar of a card tape condenser machine;

Figure 2 is a similar view but showing the parts thereof in different relation for threading roving or similar yarn therethrough;

Figure 3 is a section view taken substantially along line 3—3 showing roving with a slub thereon in a position about to be caught by the detecting portion of the slub catcher;

Figure 4 is a sectional view taken substantially through lines 4—4 of Figure 2 and showing the manner in which the device is attached to the traverse rod and the manner in which the two plates are slidably related to each other;

Figure 5 is a section view taken substantially along line 5—5 of Figure 1;

Figure 6 is a section taken substantially along line 6—6 of Figure 2; and

Figure 7 is an elevational view of a fragmental portion of one of the plates of the slub catcher shown in the above figures.

The guide and slub catcher which we provide is attached to the traverse bar of a card tape condenser and takes the place of the wire guide previously used. The device consists of a pair of slotted plates slidable one on the other to cause

2

the slots to align for receiving roving or be positioned out of line to lock the roving in desired position.

Referring to the drawings for a more detailed description of the invention, 10 designates generally a slub catcher embodying one form of our invention and comprises a member or plate 11 which may be of any desired length and preferably made of a metal material. The plate 11 (Fig. 7) is provided with a plurality of equally spaced generally vertical slots 12 the walls of which extend inwardly from the upper edge of the plate for a substantial distance and then open at right angles as at 13 to form a generally L-shaped slot. The end wall of the slot portion 13 is arcuate or semi-circular as at 15. The edges of the slots 12 may be rounded to provide a smooth surface against which the yarn or roving may engage. One end of the plate 11 is right angularly deflected as at 16 (see Figure 5) so as to provide a support 17 for an adjustable stop 18 which in the present disclosure comprises a slotted screw 19 which threadedly extends through the portion 17. A lock or jam nut 20 secures the screw 19 in adjusted position.

A second member or plate 21 of substantially the length of the plate 11 but much narrower is mounted on the plate 11 to have surface contact therewith while providing for relative longitudinal sliding movement. In the present instance this is accomplished by means of slotted openings 22, 22 there being two shown but any suitable number may be provided conditioned upon the length of the plate and the weight thereof. Stud fastenings 23 having a reduced threaded portion 24 are received through these slots 22 with the threaded portions extending through suitable openings in the plate 11, which receives jam nuts 25 to secure the studs to the plate 11 securing the plates to each other to permit slideable relation therebetween. The plate 21 is provided with a plurality of equally spaced generally vertical slots 26 the edge walls of which extend inwardly from the upper edge of the plate and with the bottom wall thereof rounded or semi-circular as at 27 and in register or in line with the bottom wall of the slots 12. The spacing of these slots 26 is made equal to the spacing of the slots 12 and of the same number thereof. The plate is

also provided with bearing openings 28 at each end thereof in which is received the lower portion 29 of manually operable lever 30 pivotally secured to the plate 11 as at 31. Thus, rocking either of said levers in one or the other direction will through contact of the lower portion 29 with

the walls of the bearing 23 move said plate slide 21 in one or the other direction relative to the plate 11. As previously stated, there is an equal number of slots 26 and 12 so that in one position of the plates relative to each other the slots 26 will be in register with the vertical portion of slots 12. This location is determined by the stud engaging against the end wall 32 of the slots 22. In this position of the slots 12, 26 roving or like textile material may be threaded into the said slots 12 and 26. Moving the handles 30 in a counter-clockwise direction as seen in Figure 2 will slidably move the plate 12 to push the roving into the angular portion 13 of the slot 12 so that the wall 26' of slot 26 will be positioned in line with or overlap the walls 12' of slot 12. This will close the angular portion of the slot 12 at the wall 26' and capture the roving in the openings 33 thus formed by the portion 13 and the wall 26' of the slot 12. In order to provide the proper size opening 33 for a particular size roving, the plate 21 is angularly deflected as at 34 (Figure 5) to provide a right angular abutment 35 in line to engage against the screw 19. Thus it will be seen that by the adjustment of the screw 19, the size of the opening 33 may be adjusted by overlapping of the walls 12' and 21' the required distance.

Tape condensing machines are usually provided with a traverse wire guide through which the roving passes to be guided on to the take-up spools. The slab catcher device of the present invention is substituted for the said usual traverse wire guide of a tape condensing machine and is attached to the traverse bar 36 thereof as by means of screw fastenings 37. Thus the slab catcher will be traversed in a manner similar to that of the said wire guide rod to guide the roving on to take-up spools, not shown.

The operation of the device has been given more or less in the detailed description of the parts thereof, and it is believed that it will suffice to state that when yarn is to be threaded into the combined guide and slab catcher, either handle 30 is moved in the proper direction so as to register the slots 26 with the vertical portions of slots 12. The roving or yarn may now be dropped into the slot 26 and the handles 30 moved in the opposite direction so as to push and confine the roving into the openings 33. The size of these openings 33 will be adjusted in accordance with the diameter of the roving passing therethrough and any slab S (see Figure 3) or other imperfection of an enlarged nature in the roving will be blocked and further tension on the roving from the take-up side of the device will break the roving. It will be apparent that if some portion of roving is of greater diameter or thickness than that of the size of openings 33, this portion of roving upon reaching opening 33 will be blocked from passing through and broken as above described.

It will now be apparent that the use of this device on card tape condensers and like machines will assure the making of a cleaner and more even yarn from a cleaner and more even roving off the cards. The slab catcher is adapted for use for wool or other fibers carded and spun on the woolen system.

We claim:

1. A slab-catcher for roving and the like textile strands comprising a first plate having a roving receiving opening extending inwardly from the upper edge thereof generally vertically for a substantial distance and then angularly thereto, a

second plate slidably mounted on said first plate and having an opening extending inwardly from the upper edge thereof generally vertically to a depth to have the bottom thereof substantially in line with the bottom of the opening in the first plate, and means for relatively slidably moving said plates to register the opening in the second plate with either portion of the opening in the first plate whereby when said opening in the second plate is in register with the angular portion of the opening in the first plate, a restricted opening with closed sides will be provided for the roving to pass through.

2. A slab-catcher as set forth in claim 1 wherein the opening in the first plate is L-shaped.

3. A slab-catcher as set forth in claim 1 wherein each of said plates has an equal number of said openings therethrough.

4. A slab-catcher for roving and the like textile strands comprising a first plate having a plurality of equally spaced roving receiving openings extending inwardly from the upper edge thereof generally vertically for a substantial distance and then angularly, a second plate slidably

25 mounted on said first plate for sliding movement relative thereto, said second plate having a like plurality of equally spaced openings extending generally vertical inwardly from the upper edge thereof to a depth for the bottom thereof to be substantially in line with the bottom of the openings in the first plate, manual means for relatively slidably moving said plates to register the openings in the second plate with either portion of the openings in the first plate, and stop means 30 carried by said plates for predetermined the amount of overlapping of the marginal edge portions of the angular portion of the openings in the first plate by the edge walls of the openings of the second plate whereby providing for predetermined size of openings the roving will pass through.

5. A slab-catcher as set forth in claim 2 wherein said stop means is adjustable.

6. In combination with a yarn traversing bar, 45 a slab-catcher having a plate fastened to said bar for movement therewith, said plate having a plurality of roving receiving openings extending inwardly from the upper edge thereof for a substantial distance and then at an angle thereto, a 50 second plate slidably mounted on said first plate for longitudinal slidable movement and having an equal number of equally spaced openings extending inwardly from the upper edge to such a depth that the bottom thereof is substantially in line with the bottom of the openings in the first plate, and means for slidably moving said 55 second plate to register the openings therein with either portion of the openings in the first plate.

7. A slab-catcher for roving and the like textile strands comprising a first plate having a roving receiving opening extending inwardly from one edge thereof for a substantial distance and then angularly thereto, a second plate slidably 65 mounted on said first plate and having an opening extending inwardly from the outer edge thereof, and means for relatively slidably moving said plates to register the opening in the second plate with either portion of the opening in the 70 first plate whereby when said opening in the second plate is in register with the angular portion of the opening in the first plate, a restricted opening with closed sides will be provided for the roving to pass through.

8. A slab-catcher for roving and the like textile

strands comprising a first plate having a plurality of equally spaced roving receiving openings extending inwardly from an edge thereof for a substantial distance and then angularly, a second plate slidably mounted on said first plate for sliding movement relative thereto, said second plate having a like plurality of equally spaced openings extending inwardly from the outer edge thereof, manual means for relatively slidably moving said plates to register the openings in the second plate with either portion of the openings in the first plate, and stop means carried by said plates for predetermining the amount of overlapping of the marginal edge portions of the angular portion of the openings in the first plate by the edge walls of the openings of the second plate whereby providing for predetermined size of openings the roving will pass through.

9. In combination with a yarn traversing bar, a slub-catcher having a plate fastened to said bar for movement therewith, said plate having a plu-

rality of roving receiving openings extending inwardly from the upper edge thereof for a substantial distance and then at an angle thereto, a second plate slidably mounted on said first plate for longitudinal slidable movement and having an equal number of equally spaced openings extending inwardly from the upper edge, and means for slidably moving said second plate to register the openings therein with either portion of the openings in the first plate.
